[57] **CLAIM**

The ornamental design for a combined liquid extraction and lid removal tool for cans, as shown and described.

DESCRIPTION

FIG. 1 is a side view of the liquid extraction and lid removal device for cans as it would be used with a standard can which is shown for environmental purposes only and forms no part of the claimed invention;

FIG. 2 is an exploded side view thereof;

FIG. 3 is a rear view thereof;

FIG. 4 is a front view thereof;

FIG. 5 is a bottom view thereof; and,

FIG. 6 is a top view thereof.
